Patented Nov. 20, 1917.

G. Hanke,
Inventor

By *Georg Kimmel*

Attorney

UNITED STATES PATENT OFFICE.

GUSTAV HANKE, OF ADDIEVILLE, ILLINOIS.

SLIDING LATCH.

1,247,397.

Specification of Letters Patent. Patented Nov. 20, 1917.

Application filed May 18, 1916. Serial No. 98,359.

To all whom it may concern:

Be it known that I, GUSTAV HANKE, a citizen of the United States, and resident of Addieville, in the county of Washington 5 and State of Illinois, have invented certain new and useful Improvements in Sliding Latches, of which the following is a specification.

The present invention relates to the class 10 of locks and latches and has particular reference to a new and useful improvement in barn door latches and the like.

The primary object of my invention is to provide a latch of the class described which 15 is simple in construction, cheap to manufacture, strong and durable and effective in operation, the device being adapted for attachment to the frame of a barn door or the like, a sliding bar member being provided 20 for engagement with the door.

Another object of my invention is to provide a latch of the class described having improved holding means associated therewith, said holding means being arranged to 25 engage with the latch member, the arrangement of the device preventing animals from moving the latch and opening the door. The latch may be used independently or 30 may be associated with other latching devices. However, I do not claim any combination between the latch and other latch devices.

Other objects and advantages to be derived from the use of my improved barn 35 door latch will appear from the following detail description and the claim, taken with an inspection of the accompanying drawing, in which:

Figure 1 is a front elevational view of a 40 latch embodying the improvements of my invention, the same being shown applied in operative position;

Fig. 2 is a rear elevational view of the same; and

Fig. 3 is vertical sectional view taken on the line 3—3 of Fig. 2 looking in the direction of the arrows.

Referring more particularly to the drawing, wherein similar characters of reference 50 designate like and corresponding parts throughout the various views, 1 and 2 designate a door frame and swinging door, respectively. The base of my improved latch is designated 3 and is preferably mounted 55 on the door frame 1 adjacent the door. The latch body 3 is in the form of a rectangu-

lar frame provided with a transverse recess 4 on the rear face thereof. The base 3 is secured to the door frame 1 by means of screws 5 or the like.

The latch base 3 is also provided with a longitudinally arranged passage 6 opening at the lower end of said body and communicating with the recess 4. A rod 7 is slidably mounted in the aperture 6, the upper free end of the rod 7 being provided with a laterally bent tongue 8 for a purpose which will hereinafter appear. A supplemental recess 9 is provided in the base 3 communicating with the recess 4 for a purpose which will hereinafter appear.

The bolt arm is designated 10 and is provided with enlargements 11 and 12 on the free extremities thereof, said enlargements extending outwardly from the door and 75 door frame. The bolt arm 10 is provided with a pair of oppositely arranged notches 13 adjacent one end thereof, said notches serving the purpose which will hereinafter appear.

The lower end of the rod 7 is provided with a finger engaging portion 14 for manipulating said rod vertically in the passage 6.

In use, the base of the latch is applied 80 to a door frame as best shown in Fig. 1. The bolt arm 10 is first placed within the recess 4 and the base 3 coöperates with the door frame for retaining said bolt arm in operative position. When moved into the 85 position shown in Fig. 2 the rod 7 becomes engaged with the bolt arm by virtue of the tongue 8, said rod dropping by gravity whereby the tongue 8 engages in one of the notches 13. Two of the notches are provided 90 in order that the device may be reversed when desired, thereby facilitating application of the device to various types of doors, without altering the construction of the door or of the device. The holding 95 rod 7 is an automatic locking means for the bolt arm 10, said arm extending across a portion of the door 2 as shown in Fig. 1 for retaining the door in closed position.

It will be readily apparent that I have 105 provided in my improved latch a simple and effective means for application to doors of various types. It will also be readily apparent that the device may be used in combination with the ordinary latch devices 110 without altering the construction of my improved latch.

From the above description taken in connection with the accompanying drawing, it is thought that a clear and comprehensive understanding of the construction, operation and advantages of my invention may be had, and while I have shown and described my invention as embodying a specific structure, I desire that it be understood that such changes may be made in said structure as do not depart from the spirit and scope of the invention as claimed.

Having thus fully described my invention, what I claim as new and desire to secure by Letters Patent, is:—

15 A latch of the class described including an elongated base member, said member having a transversely extending recess in one face thereof, the upper wall of said recess having a supplemental recess formed 20 therein, a bolt arm slidably mounted in the transversely extending recess with its side edges engaging the side walls of the same,

said arm being provided with a notch in one edge adapted for alinement at times with the supplemental recess in its adjacent side wall, said base member having a longitudinally extending passage therein communicating at its upper end with the bolt arm receiving recess at a point diametrically opposite the supplemental recess, 30 a gravity operable locking rod slidably mounted through said passage and having its upper end extending into the recess, and a laterally extending tongue on the upper extremity of said rod when inoperative 35 adapted to be normally positioned in the supplemental recess and to slide on the adjacent edge of the bolt arm, said tongue being adapted to drop into the notch in said arm when the notch and the supplemental recess are alined.

In testimony whereof, I affix my signature hereto.

GUSTAV HANKE.
